UNITED STATES PATENT OFFICE.

ROBERT J. SCHUYLER, OF MEXIA, TEXAS.

AUXILIARY OIL SAVER.

Application filed June 24, 1922. Serial No. 570,676.

To all whom it may concern:

Be it known that I, ROBERT J. SCHUYLER, a citizen of the United States, residing at Mexia, in the county of Limestone and State 5 of Texas, have invented certain new and useful Improvements in Auxiliary Oil Savers, of which the following is a specification, reference being had to the accompanying drawings.

10 At times when breaking the joints of oil well tubes or pipes, which are taken apart in sections, for the purpose of cleaning well tubes or repairing the same, the oil from the disconnected sections is permitted to run 15 to waste. To save this waste oil, savers in the form of housings (which include discharge means) have been employed for connecting the sections, when breaking joints for repairs and cleaning.

20 Such oil savers are not effective and practical for use in connection with pumping or flowing wells when in action, or for use in connection with swabbing wells.

At the present time, in connection with 25 pumping, flowing or swabbing wells, or while drilling, to save oil or gas waste, there is now being used what is known as a roller oil saver, which is used immediately above and connected to the top of the control 30 head of the well pipe. This character of oil saver serves its purpose reasonably well, and acts to put considerable of the waste oil into the tank. However there still exists a waste of the oil, due to a certain amount 35 of the oil clinging to the pump rod, or to a cable, which is used for pulling a swab, when swabbing a well. The waste of oil from this result particularly increases when the wiping rubbers of the roller oil saver 40 become so worn that they will not serve their purpose when adjusted.

It is, therefore, the purpose of the present invention to provide an oil saver to be used as an auxiliary roller oil saver. For instance in a short while the wiping rubbers of the roller oil saver become worn, therefore a considerable amount of oil clings to the swabbing cable, or to a pump rod, and to carry this waste oil, which discharges at 45 the top of the roller oil saver, to the tank, the auxiliary oil saver is mounted below the control head of the well tube, and also below the flooring of the derrick, so that when the waste oil discharges from the top

of the roller oil saver it will be carried into 55 the auxiliary oil saver, and from thence to the tank.

This improved character of oil saver is especially adapted for use in connection with pumping or flowing wells or for use 60 in connection with swabbing wells, when pulling a swab, and which is in the form of a funnel clamped with a packing to the oil tube below the control head, including a connection with the piping leading 65 to the tank, so as to carry this waste oil to such container.

Another purpose is to provide means immediately below the floor of the derrick and assuming a position reaching over a considerable area of the flooring of the derrick and overlying the upper margin of the funnel for carrying the waste oil thereinto. This character of auxiliary oil saver 70 may be used as an auxiliary, even in connection with such oil savers which are used, when breaking the joints of oil tubes, which are taken apart in sections, for the oil which may flow over the flooring of the derrick, at the time of separating the sections of the 75 tube, will flow into the funnel, and be carried off to the tank.

A further purpose is the provision of an auxiliary oil saver constructed in sections including packing therebetween so as to be 80 easily and quickly applied to the well tube.

It has also been found that there is considerable oil absorbed by the cable when swabbing a well, even though a roller oil saver may be employed. The oil which 85 clings to the cable is carried over and drips from the bull wheel onto the floor of the derrick, and drips between the boards and eventually goes to waste. It is also the aim 90 to save this waste of oil, by the provision of a drip trough or pan mounted upon the flooring of the derrick, including a tube or pipe leading therefrom and connected to the pan or trough which is immediately above the auxiliary oil saver funnel, whereby the 95 oil which is carried to the bull wheel, is also carried off to the tank with the oil which wastes from the top of the roller oil saver.

A still further purpose is to provide an auxiliary oil saver, which will relieve the 100 necessity of keeping the adjusting means of the wiping rubbers or shoes of the roller oil saver too tightly adjusted, and will there- 105

by prolong the life of such wiping rubbers or shoes.

5 It is to be understood that the particulars herein given are in no way limitative and that while still keeping within the scope of the invention, any desired modifications of detail and desired proportions may be made in the apparatus according to circumstances.

10 The invention comprises further features and combination of parts, as will be hereinafter set forth, shown in the drawings and claimed.

In the drawings:—

15 Figure 1 is a view in perspective of a portion of the flooring of an oil well derrick, showing an oil well tube and its control head, including the roller oil saver, and also illustrating the auxiliary oil saver as applied.

20 Figure 2 is a sectional view through the same, showing the control head in elevation, and illustrating a portion of the roller oil saver in section;

25 Figure 3 is a plan view of the drip pan or trough, which is disposed immediately below the flooring of the derrick and immediately above the auxiliary oil saver funnel, showing the pan or trough dished, and constructed in sections;

30 Figure 4 is a sectional view on line 4-4 of Figure 3;

Figure 5 is a sectional view through the auxiliary oil saver funnel more clearly showing the construction thereof;

35 Figure 6 is a sectional view on line 6-6 of Figure 5;

Figure 7 is a sectional view on line 7-7 of Figure 5, showing how the cylindrical base portion of the auxiliary oil saver funnel is constructed.

45 Referring to the drawings, 1 designates the flooring of the oil well derrick, and mounted upon supporting cleats 2 which rest upon the flooring, is a drip pan or trough 3. This drip pan or trough 3 is supported in position below the bull wheel 4, on which the swabbing cable 5 winds. The pan or drip trough 3 is dished from its sides and ends toward its center, which is provided with a discharge opening 6, to which a pipe or tube 7 is connected. It is to be noted that Figure 50 1 discloses the auxiliary oil saver device as applied to a well pipe or tube, from which a swab is being withdrawn. A lever is

55 a swab is being withdrawn. As shown in Figures 1 and 2, the usual roller oil saver 8 is applied in position immediately above the control head 9 of the oil well tube. The control head is considerably stronger than the oil well casing or tube.

60 the oil well casing or tube, so as to withstand high pressures, and connected to the control head is an oil conveying pipe or tube 10, which connects with a pipe or tube 11, which carries the oil from the well to a storage tank (not shown).

65 As shown in Figure 2 the roller oil saver,

which is at present used, comprises a casing 12, which has mounted therein guide rollers 13, between which the cable 5 which connects with the swab (not shown) fastens. The roller oil saver casing also carries a pair of diametrically opposite wiping rubbers or shoes 14, there being opposed plates 15 operated by the adjusting screws 16 of the usual character, for adjusting the wiping rubbers or shoes toward and from the cable. The wiping rubbers or shoes act to wipe the oil from the cable, as it is pulled through the roller oil saver. The opposite rollers 13 act to guide the cable, and keep it from irregularly binding on the rubbers or shoes, and also prevents the cable from unevenly wearing the shoes or rubbers. As previously stated, even though the shoes or rubbers act to wipe off the oil, there is considerable of the oil still carried by and absorbed in the cable. This oil discharges from the top of the roller oil saver, and down upon the exterior of the control head, and drips therefrom onto the flooring, some of it passing down upon the exterior of the well pipe and going to waste. Other parts of this oil feeds over with the cable, and drips from the bull wheel, which has heretofore gone to waste. However in order to collect this waste oil a pan or trough 17 is placed beneath the flooring of the derrick, and supported in any suitable manner. The pan or trough is dished from its sides and ends, and comprises two sections 18, which are fastened together by means of bolts or the like 19. The bolts 19 pass through the flanges 20, which are carried by the adjacent edges of the two sections of the pan or trough, and also through a packing 21, which is arranged intermediate the flanges, to insure against leakage of the oil. The pan or trough 17 has an opening 23, of substantial diameter, the marginal edge of which has a slightly turned down flange 24, which overlies and is spaced from the marginal edge of the mouth of the auxiliary oil saver funnel 25, so that any oil that passes between the boards of the flooring of the derrick, will flow into the trough or pan 17, and thence flow into the funnel oil saver 25. This funnel oil saver 25 comprises two sections 26 and 27. The conical portions of these sections have lateral flanges 28, between which, a packing, such as rubber or the like 29 is arranged. Suitable bolts 30 pass through the flanges 28 and the packing, to insure a tight joint between the sections, and to prevent leakage of the oil. The lower portions of the two sections 26 and 27 terminate in semi-cylindrical parts 31 and 32. These semi-cylindrical portions overlap each other, and interposed between the semi-cylindrical portions and the well tube or pipe 33 is a suitable packing or rubber or any other suitable material 34, to insure against leakage of oil. Semi-cylindri-

- cal bands 35 engage about the semi-cylindrical portions 31 and 32, and have lateral ears 36, through which the bolts 37 engage, for drawing the flanges 36 together and tightening the semi-cylindrical bands 35 in position. These bands 35 act to draw the semi-cylindrical portions against the packing 34, to prevent the leakage and waste of oil from the funnel. A suitable pipe 38 is connected 10 by means of a packed joint or union 39 with the conical wall of the section 27 of the funnel oil saver 25, and is in turn connected to a tank 40. A pipe 41, which carries a gate valve 42 and a conventional form of check 15 valve 43 extends a substantial distance into the T-fitting 44 of the pipe 11, as indicated at 45. The gate valve 42 is employed for cutting off the supply of oil from the tank 40, whereas the conventional form of check 20 valve 43 is provided for the purpose of preventing a retrograde flow of the oil. It will be noted that the greater portion of the oil passing through the pipe 10 at the junction of said pipe with the pipe or tube 11, creates 25 an injector action and tends to draw the oil from the portion 45 of the pipe 41, thereby carrying the waste oil together with the main supply of oil to the storage tank.
- The oil that may be absorbed by the cable 30 5, when its considerable length is wound upon the bull wheel, drips into the pan or trough 3, and due to the pipe 7 being slightly inclined, it is carried to the drip pan or trough 17, from whence the oil 35 passes through the opening 23 into the conical funnel shaped auxiliary oil section. It is obvious that the auxiliary oil saver collects the oil which has been heretofore lost by the roller oil saver, and which still drips 40 from the cable on the bull wheel. In fact any oil that may be allowed to waste upon the flooring of the derrick, particularly adjacent the oil well tube or pipe, will flow into the drip pan or trough 17, and will be 45 conveyed to the funnel shaped auxiliary oil saver.
- The invention having been set forth, what is claimed is:—
1. An oil saver for well drilling rigs 50 comprising a pan adapted to be mounted upon the oil pipe below the control head thereof and below the floor of the rig, said pan having a relatively large central opening, a downwardly tapering portion extending downward from said opening and at its lower end formed to be clamped upon the oil pipe, said pan being formed in two sections and having means whereby the sections may be clamped to each other, and
  2. An oil saver for well drilling rigs comprising a pan adapted to be mounted upon the oil pipe below the control head thereof and below the floor of the well drilling rig, said pan having a relatively large central opening and downwardly tapering walls surrounding the opening and formed at their lower ends to be clamped upon the oil, a second pan adapted to be disposed below the bull wheel to receive oil dropping therefrom, and a pipe connecting the second named pan with the first named pan.
  3. An oil saver for well drilling rigs comprising a pan adapted to be mounted upon the oil pipe of the rig below the control head thereof and below the floor thereof to receive drippings therefrom, said oil pan having a relatively large central opening and a downwardly tapering portion adapted to be clamped at its lower end upon the oil pipe, a tank disposed on a lower level than the pan, a pipe leading from the downwardly extending portion to said tank and discharging thereinto, a discharge pipe leading from the tank, a second pan adapted to be disposed beneath the bull wheel of the rig and receiving drippings therefrom, and a pipe leading from the second named pan to the first named pan.
  4. The combination with an oil well derrick including an oil well tube and flooring through which the tube passes, a control head mounted upon the tube, a pipe leading from said control head and having a downwardly extending discharge portion, of an oil saver comprising a pan mounted upon the oil pipe immediately below the flooring of the derrick and below the control head and receiving drippings therefrom, said pan having a relatively large central opening through which the oil pipe passes and having a downwardly extending conical portion engaged with the pipe and having a pipe leading to said tank, a second pan disposed below the bull wheel and receiving drippings therefrom, a pipe leading from the second pan and discharging into the first named pan, a pipe leading from the conical portion of the first named pan, a tank into which the pipe discharges, and a pipe leading from the lower end of the tank and discharging into the main discharge pipe.

In testimony whereof I hereunto affix my 115 signature.

ROBERT J. SCHUYLER.
